UNITED STATES PATENT OFFICE.

LEWIS G. McCCLINTOCK, OF PITTSBURGH, PENNSYLVANIA, ASSIGNOR TO PITTSBURGH TRANSFORMER COMPANY, A CORPORATION OF PENNSYLVANIA.

COOLING APPARATUS FOR TRANSFORMERS.

Application filed September 1, 1922. Serial No. 585,596.

To all whom it may concern:

Be it known that I, LEWIS G. McCCLINTOCK, a citizen of the United States, residing at Pittsburgh, in the county of Allegheny and State of Pennsylvania, have invented certain new and useful Improvements in Cooling Apparatus for Transformers, of which the following is a specification.

10 This invention relates to electrical transformers and particularly to cooling means for the oil of a tank in which the transformer is submerged. The chief object of the invention is to provide cooling apparatus which will maintain the circulating oil in the form of a thin downwardly flowing layer or sheet and which at the same time will increase the efficiency of a cooling action by giving the said sheet a compact, 15 folded or corrugated form in vertical parallel strips arranged at angles to each other.

Other objects of the invention, particularly in providing a cooling apparatus combining strength and simplicity of structure, will appear from the following description taken in connection with the accompanying drawings in which—

Fig. 1 is a vertical elevational view of a transformer tank provided with cooling apparatus illustrating the invention.

Fig. 2 is a vertical sectional view of a portion of Fig. 1.

Fig. 3 is a diagrammatic plan view of apparatus shown in Fig. 1.

Fig. 4 is a detached perspective view of one of the coolers.

Fig. 5 is a plan view of the same.

Fig. 6 is a detailed sectional view of the structure shown in Figs. 4 and 5.

40 In the specific apparatus shown in the drawings illustrating one embodiment of the invention a tank K containing a transformer T immersed in oil to a level L is connected by upper and lower pipe connections 9 and 10 with cooling apparatus comprising usually a series of separate coolers C (Fig. 3). Each cooler C comprises an outside wall 11 and an inside wall 12 spaced apart a relatively small distance D so that

45 the circulating oil flowing down between them is in the form of a thin sheet moving downwardly at all portions and without any dead portions or countercurrents. To give as full and rapid a circulation as possible through the cooler C the pipe connec-

tions 9 and 10 are very large in cross section area and are preferably, for instance, of a combined area equal approximately to the cross section area of the passage through the cooler C.

50 In order to provide a compact efficient form to the cooler C its inner and outer sides of walls 11, 12 are folded or corrugated while at the same time retaining the general parallel relation between these 55 walls. Each cooler is thus shaped to form a series of vertical strips a, b, c, d, e, f, etc., at an angle to each other and in zigzag form while still preserving the unity and continuity of the sheet of circulating oil. By 60 this formation the overall horizontal dimensions of the cooler are reduced while still maintaining the full extent of the cooling area, thus permitting a larger number of coolers to be placed within a given space. 65

The supply and return pipes 9 and 10 are connected to the inner wall 12 at the top and bottom and are preferably arranged so as to partially straddle the ridge formed by the portions c, d, the apex of the angle between these portions being located at about the center of the pipe connections and the ends of the pipes being bifurcated so as to extend along the surfaces c, d, of the plate or wall 12 to be welded thereto as indicated 70 at 15, 16. The passage between the walls 11, 12 at the areas at connections to pipes 9, 10 thus extends in the same general direction of said pipes to smoothly receive, distribute and return the oil. At the same time 75 the extended connections 15, 16 of the pipes 9, 10 with the cooler C give a strong joint adapted to safely sustain the weight of the cooler and its contained body of oil.

80 In the formation of the cooler C shown 85 in the drawings the sheets or plates 11, 12 are similarly folded or corrugated so as to be substantially parallel to each other and rods 20, 21 similarly bent or corrugated along zigzag lines to fit between side plates 90 or walls 11, 12 at their ends as shown in Fig. 2. Welds are then formed between the rods and the adjacent edges of the pipe to close and rigidly support the ends of the cooler C. The vertical side edges are preferably closed over and welded as shown 100 in Fig. 2 in which the outer plate 11 has its end 22 bent over at 23 to form a groove in which the welding metal 24 is deposited.

105 The cooler of this invention is thus simple 110

and inexpensive in formation and strong and durable. The longitudinal folds or corrugations greatly increase its strength and rigidity by the succession of connected arches thus formed. At the same time the volume of oil in the cooler is relatively small due to the close spacing of the walls 11 and 12, thus further saving in the first cost of the oil required to fill the tank and coolers.

10 In lieu of welding the parts together they may be fastened by brazing or in any other suitable manner.

I claim:

15 1. Cooling apparatus comprising a cooler adapted to be spaced from a tank and connected thereto said cooler comprising two complementary corrugated sheets spaced apart at the top and bottom by spacing rods 20 and welded thereto, and the side edges of one plate being bent over and welded to the other plate.

25 2. An apparatus comprising a tank, a cooler spaced from said tank, comprising two complementary corrugated sheets spaced apart to form a thin corrugated space and pipe connections joining the interior of said tank and said space, said pipe connections having 30 passages whose combined area is at least substantially equal to the area of said space transverse to said corrugations.

30 3. An apparatus comprising a tank, a

cooler spaced from said tank comprising two complementary corrugated sheets spaced apart to form a thin corrugated space and pipe connections joining the interior of said tank and space having passages which are directed normal to said cooler, and which communicate with said space at an inner bend of a corrugation, whereby fluid leaving or entering the said passages is guided without sudden change in direction, transversely of said corrugation.

4. An apparatus comprising a tank, a cooler spaced from said tank comprising two complementary corrugated sheets spaced apart to form a thin corrugated space, pipe connections joining the interior of said tank and said space, said pipe connections having 45 passages communicating with said space at an inner bend of a corrugation and having 50 a combined area at least substantially equal to the area of said space transverse to said corrugations.

5. An apparatus comprising a tank 55 having a curved wall, coolers spaced at intervals from said wall, each cooler formed to follow the curvature of said wall and comprising two complementary corrugated sheets welded together at their edges and 60 spaced apart between their edges to form a narrow corrugated space.

LEWIS G. MCCLINTOCK.
